ABSTRACT OF THE DISCLOSURE

The device comprises top and bottom U-shaped frame sections for retaining a filter panel therebetween. The top and bottom section have respective oppositely disposed triangular cutouts, whereby the top and bottom frame sections may be folded to provide an angular filter construction.

This invention relates to panel filter construction, and, more particularly, to such a construction that permits forming a plurality of planar filter sections angularly disposed with respect to one another.

Various forms of filter constructions are well known in the art. However, these constructions generally apply to forming corners in the frames that enclose planar filter elements, and in no way affect the shape of the filter element. In general, they provide mitered corners in a single-piece frame construction, or brackets in a multi-piece construction for holding the adjoining sections together. In other constructions, the frame section may be welded or brazed together.

The present invention differs completely from the constructions previously known in that it is not directed to the formation of corners for the four corners of a planar filter panel. Rather, it is directed to construction of a plurality of planar filter sections from a single filter section comprising a single filter panel retained within a single frame. Except for the teachings of the invention, the frame may be of conventional construction.

Basically, the filter construction of the invention comprises top and bottom U-shaped frame sections with a filter panel retained therebetween. The top and bottom frame sections have respective oppositely disposed triangular cutouts, which define a fold line. The top and bottom frame section, with the filter panel retained therebetween, may be folded along the fold line to provide a plurality of filter sections angularly disposed with respect to one another.

Further features and advantages of the invention will become apparent from the following description, taken in conjunction with the accompanying drawings, in which:

FIGURE 1 is a perspective view of a filter embodying the invention before the filter is folded;

FIGURE 2 is a perspective view of the filter of FIGURE 1 after it is folded;

FIGURE 3 is a perspective view of a portion of the top frame section showing a triangular cutout;

FIGURE 4 is a perspective view of a portion of the top frame section showing the folded corner; and

FIGURE 5 is a sectional view taken on the line 5—5 of FIGURE 4.

FIGURE 1 is a perspective view of a filter embodying the invention before the filter is folded to form a plurality of sections. The filter comprises a frame, shown generally by the numeral 10, having top and bottom sections 11 and 12, respectively, and side sections 13 and 14. The frame 10 retains a filter panel 15. The construction of the mating corners of the frame sections 11, 12, 13 and 14 is of no particular importance and is not part of the present invention.

Each of the frame sections 11—14 is U-shaped in cross-section and has side portions denoted *a* and *b*, and a top

2

portion denoted *c*. The frame sections 13 and 14 are substantially identical, and frame sections 11 and 12 are substantially identical. If it is desired to fold the filter to form two sections, a triangular cutout 11d is made in the top portion 11c, and a similar cutout 12d is made in the top portion 12c (not shown). The cutouts 11d and 12d are opposite each other and their vertices *e* define a fold line 16, as best seen in FIGURES 2 and 4. The bases of the cutouts are essentially parallel to and adjacent to the junctures of the portions *b* and *c* of the frame sections 11 and 12. The vertices *e* are adjacent the junctures of the portions *a* and *c* of the sections 11 and 12. Thus, each cutout *d* substantially spans a portion *c* of a frame section.

The angles of the vertices 11e and 12e determine the degree of fold that can be placed in the filter without overlapping the edges of the top portions 11c and 12c or leaving a space between adjacent edges. Thus, the cutouts may be triangles of virtually any desired angular configuration, such as 90°—45°—45°, 60°—60°—60°, etc., to provide different angles of bend that form neat corners in the filter. The cutouts shown form 90°—45°—45° triangles to provide a 90° fold in the filter, as shown in FIGURES 2, 4 and 5.

It is also pointed out that the invention is not limited to only one cutout in each of the portions 11c and 12c. If it is desired to provide a filter having more than two folded sections, a plurality of matching cutouts may be provided in the portions, spaced apart as desired to provide a plurality of fold lines. Thus, a "zig-zag" or other configuration may be provided.

FIGURES 4 and 5 illustrated the construction of the fold in detail. As shown in FIGURE 5, when the frame section 11 is folded about the fold line 16, a part of the portion 11b, designated 11f, is folded inwardly toward the portion 11a. This compresses the filter panel 15 opposite the fold line 16. Thus, the filter material must be sufficiently compressible to produce an acceptable appearing corner.

What is claimed is:

1. A panel filter construction comprising:

top and bottom U-shaped frame sections for retaining a filter panel therebetween;

each said frame section having two side portions and a top portion;

each of said top portions having, in alignment, at least one triangular cutout therein;

each said triangular cutout having a base substantially parallel to a first side portion and a vertex adjacent a second side portion on the same side of said frame sections; and

each said cutout substantially spans said top portion of said frame section.

2. The construction defined by claim 1, wherein cutouts form substantially 90°—45°—45° triangles.

3. The construction defined by claim 1, wherein said vertices have substantially 90° angles.

4. A panel filter construction comprising:

top and bottom U-shaped frame sections, each having two side portions in parallel and joined by a top portion so as to define a pair of opposing elongated channels for retaining a filter panel therebetween; and

said top portions being formed with aligned triangular cutouts wherein each cutout has a base substantially parallel to a selected side portion on the same side of said construction and a vertex adjacent the other side portion on the other side of said construction.

5. The construction defined by claim 4, wherein each said cutout substantially spans said top portion of said frame section.

6. The construction defined by claim 4, wherein the two vertices define a fold line along said selected side portions for said frame sections.

7. The construction defined by claim 6, wherein said frame sections are folded about said fold line.

8. The construction as defined in claim 4 wherein material of said side portions in alignment with said vertices constitutes a deformable fold line adapted to be displaced into said respective channels when said frame sections are folded about said fold line.

9. The construction as defined in claim 4 wherein material of said side portions is displaced into said respective channels when said selected side portions are moved about an axis defined by the alignment of said two vertices.
